UNITED STATES PATENT OFFICE.

HARRY H. RUSSELL, OF PORTLAND, MAINE, ASSIGNOR TO THE E. T. BURROWES COMPANY, OF PORTLAND, MAINE, A CORPORATION OF MAINE.

FOLDING STOOL AND LADDER.

1,333,344.

Specification of Letters Patent.

Patented Mar. 9, 1920.

Application filed May 17, 1918. Serial No. 235,088.

To all whom it may concern:

Be it known that I, HARRY H. RUSSELL, a citizen of the United States, and resident of Portland, county of Cumberland, State of Maine, have invented an Improvement in 5 Folding Stools and Ladders, of which the following description, in connection with the accompanying drawings, is a specification, like characters on the drawings representing like parts in each of the several 10 views.

This invention relates to an article of furniture adapted for optional use either as a stool to afford a standing area or seat for 15 the user, or as a short step ladder as required, with a capability of being folded up into very compact form to be laid away when not in use. A prime object of the invention is to provide a device of this kind 20 that is capable of being instantly opened from a folded condition, for use as a stool or ladder, and when so opened is constructed and adapted to assume automatically an assembled condition in which it is held rigid 25 and secure against shaking or racking displacement under the weight of the user so that not only is the structure actually made stronger, but a feeling of confidence is inspired in the user and even a timid person 30 standing on the seat surface of the stool would be in no fear of falling. To this end I provide means whereby the ladder element as it swings into operative position with respect to the top, is automatically 35 wedged into special receiving seats or sockets of the top to impart stiffness and rigidity to the structure while having a capability of instant and free release when the ladder is to be folded up. The invention also has 40 to do with improved means for holding the ladder element securely braced and rigid with respect both to the top or seat and to a rear leg element which is operatively connected thereto. The invention also consists 45 in providing for the seating of an angular extremity of the ladder element in a socket or recess in the top correspondingly shaped to fit the same whereby the parts are mutually interbraced and stiffened in use. The 50 foregoing and other objects and advantages of the invention will more fully appear from the following detailed description, and the distinctive features of novelty will be pointed out in the appended claims.

Referring to the drawings:

55

Figure 1 shows in side elevation a combination stool and ladder formed in accordance with my invention set up in position for use;

Fig. 2 is an elevation showing the same 60 folded or collapsed;

Fig. 3 is an enlarged sectional detail on line 3—3 of Fig. 4 showing my improved co-operative formation of the top and the ladder element, which is hinged to fit into the 65 correspondingly shaped recess in the top; and

Fig. 4 is a sectional detail on line 4—4 of Fig. 3.

The top of my improved device is indicated at 10, and is of a size to afford a convenient standing area or seat as the case may be when the device is used as a stool and has any desired peripheral outline, though shown as octagonal as this form affords a maximum of seating area without presenting unduly projecting corners. Adjacent the rear of this top is hinged at 11 a rear leg element 12 which is usually in practice made up of spaced apart leg members 70 to support the opposite sides of the top, suitably interbraced as is common. Toward the front of the top 10, and as shown, some little distance in advance of the center of the top is pivoted as at 13 a ladder element 75 14, the pivots 13 and 11 being parallel. The portion of the top 10 extending in front of the pivots 13 is adapted to serve as a lever extremity equipped with a hand hold 10^a so that when the device is picked up by means 80 of this hand hold, it will automatically swing into folded position. The ladder element 14 is preferably made with spaced apart sides as is usual having fixed therebetween a series, shown as two, of ladder 85 steps 15. A brace or strut element 16 is pivoted to the leg element at a point 17 relatively low down and remote from the top 10 and is likewise pivoted to the ladder element 14 at 18 relatively high up and near 90 to the top 10. In practice, this brace element is preferably made of metal and it and its pivot pins are strong and capable of resisting both tension and compression strains. One of these braces or struts 16 may of 95 course be employed at each side of the ladder.

It will be noted that the side pieces or

rails of the ladder element 14 are of some little width with the hinges 13 at the inner top corners thereof and in accordance with my invention the tops of these rails or side 5 pieces have their ends squared off as seen at 19, or formed so that when the ladder extends at a substantial incline, with the device set up for use as seen in Fig. 1, this squared off end with its corner 20 opposite 10 the corner where the hinge 13 is secured, extends up into the plane of the top to a considerable extent. These corner portions 20 of the ladder rails are beveled at their sides as seen at 21, and also as shown at the front 15 thereof as seen at 21^a, and the top is formed with correspondingly beveled sockets or recessed seats 22 into which the corners 20 are adapted to be pressed with a degree of wedging action as the ladder swings out- 20 ward to operative position. Thus when the ladder is opened for use these projecting corner portions fitting and wedging tightly into the seats therefor in the top make the entire structure rigid and strong to resist 25 racking or twisting motion or looseness of any kind and give a feeling of security to the user who might be standing on the platform or top 10, whereas if the tops of the ladder rails merely rested against the under 30 surface of the platform 10, such platform if used to stand on would still have the racking or shaking tendency which has heretofore been a universal attribute and objection to stools of this kind so far as known to 35 me. It is to be further noted that while the ladder is thus rigidly and securely assembled with the top or platform in use, by reason of the fact that the swinging movement is about the pivot 13 which is 40 close to the wedging parts and since the folding movement exerts initially a substantially straight pull of such corners out of their wedge sockets, there is no danger of the wedging action in question at all in- 45 terfering with the folding up movement of the device. As will be observed from Fig. 2 the parts can be instantly folded together to a very compact form with the rear legs alongside the ladder 14, and when required 50 for use it is only necessary to swing the legs 12 upward and outward until the top 10 comes to the horizontal position when the beveled corners 20 of the ladder top will fit and wedge into the recesses 22 as described, 55 locking and holding the parts rigid and secure for use. It is to be noted that this recessing and wedging of the corners 20 of the ladder top into the top 10 not only sustains and takes up any tendency to rack- 60 ing or twisting motion but it also takes the forward strains from the hinges and otherwise relieves the same to a large degree and makes the device altogether much more stable and substantial than would be the case 65 were the top 10 merely resting on the top of

the ladder with a hinge connection, I preferably make the braces 16 straight and strong so that there is no spring or yield thereto as would be the case with curved or angular braces. A bolt 25 is shown as passed 70 through the ladder near the end thereof partly to coöperate for holding the leaf of the hinge assembled therewith and partly to reinforce the top itself. The construction of the device may be varied as to certain 75 details without departing from the spirit of the invention and I therefore desire the present embodiment to be considered as illustrative and not restrictive, referring rather to the appended claims to indicate 80 the scope of the invention.

Having described my invention, what I claim as new and desire to secure by Letters Patent is:

1. A folding stool and ladder, comprising 85 a top constituting a platform or seat, a rear leg member hinged to the top adjacent the rear thereof, a ladder member hinged to the top toward the front thereof, and a brace pivoted to said rear leg member relatively 90 remote from its hinge and pivoted to said ladder member relatively near its hinge, said ladder member having side rails presenting relatively wide top portions with the hinge connection to the top at the inner edges 95 thereof and presenting beveled corners extending within the plane of said top when in inclined operative position, and said top having bevel walled recesses into which the beveled corners of said ladder side rails fit 100 and are pressed home with a lever action by weight resting on said platform to hold said top platform against racking or shaking movement and support the hinge against forward strain.

2. A folding stool and ladder, comprising 105 a top constituting a platform or seat, a leg member hinged adjacent the rear thereof, a ladder member engaged therewith by hinges toward the front thereof, a brace pivoted to 110 said leg member relatively low down and far from its hinge and pivoted to said ladder member relatively high up and near its hinge, said parts being formed and arranged to present said ladder member in substantially inclined position and said leg member relatively near the vertical when supporting the top horizontally, said ladder member having side rails presenting relatively wide top portions with corners projecting up into 115 the plane of the top when the top is in horizontal operative position, said corners beveled laterally, and said top having recesses formed to receive said projecting corner portions with a wedging action whereby 120 the device is held against racking or shaking movement.

3. A folding stool and ladder, comprising 125 a top constituting a platform or seat, a rear leg hinged toward the back of said top, a 130

ladder element hinged toward the front of said top, and a brace pivoted to said rear leg and to said ladder element at different distances from the hinges thereof, said parts 5 being formed and arranged for said ladder element to support said top horizontally while being itself substantially inclined outward and with said rear leg relatively near the vertical, said ladder element having its 10 top end squared off with its hinge connection to the top at the inner side thereof whereby it presents a corner projecting up into the top when in operative position, said corner having its sides beveled adjacent said hinges, 15 and said top being recessed and presenting walls adapted to receive said beveled corners with a wedging action and serving as diagonal abutments to resist forward strains.

4. A folding stool and ladder, comprising 20 a top constituting a platform or seat, and a ladder pivoted thereto and equipped with means for holding it either in operative position or in a folded inoperative position, said ladder having side rails presenting corners extending up into said top when in operative position, said top having recesses to receive said corners, and said corners and recesses being coöperatively formed and arranged with respect to said pivot to cause 25

said corners to wedge into said recesses when 30 said ladder is in operative position.

5. A folding stool and ladder, comprising a top constituting a seat, a rear leg hinged toward the back of said top, a ladder element hinged toward the front of said top, 35 and a brace pivoted to said rear leg and to said ladder element at different distances from the hinges thereof, said parts being formed and arranged for said ladder element to support said top horizontally while 40 being itself substantially inclined outward and with said rear leg relatively near the vertical, said ladder element having its top end squared off with its hinge connection to the top at the inner side thereof, whereby it 45 presents a corner projecting up into the top when in operative position, and said top being recessed to receive said projecting corner and presenting walls fitting the same and serving as diagonal abutments adjacent 50 said hinges to resist forward strains, said squared off top of the ladder element being automatically pressed home into said top seat by pressure on said top seat.

In testimony whereof I have signed my 55 name to this specification.

HARRY H. RUSSELL.
